INSULATOR RACK

John V. Majewski, Milwaukee, Wis., assignor to McGraw-
Edison Company, a corporation of Delaware

Application June 14, 1955, Serial No. 36,502

Term of patent 14 years

(Cl. D26—9)

Fig. 1

Fig. 2

Fig. 1 is a fragmentary perspective view of an insulator rack, showing my new design; and

Fig. 2 is a fragmentary side-elevational view thereof.

The full lines in the drawing disclose the characteristic features of the present design. The full line representation of the present rack design has been broken intermediate the ends of the rack to indicate that the design is repetitive throughout the rack length for the desired number of projections adapted to receive the insulator supporting rod, shown dotted for illustrative purposes only.

The dotted line showing an insulator and supporting rod in Fig. 2 is for illustrative purposes only.

I claim:

The ornamental design for an insulator rack, as shown and described.
